UNITED STATES PATENT OFFICE.

DAVID H. HARNLY, OF CHICAGO, ILLINOIS.

AWNING.

Application filed October 6, 1921. Serial No. 505,725.

To all whom it may concern:

Be it known that I, DAVID H. HARNLY, a citizen of the United States, and resident of Chicago, county of Cook, and State of Illinois, have invented certain new and useful Improvements in Awnings, of which the following is a specification and which are illustrated in the accompanying drawings, forming a part thereof.

10 The invention relates to awnings and has for its object the provision of an improved device, which, while of exceedingly simple construction, is capable of use in a plurality of desirable positions, is readily applied to 15 and removed from the window and when furled, occupies a position at the top of the window whereby the entire window opening is unobstructed. A further object is to provide fixtures which are readily secured 20 in the window frame for firmly holding the awning in any adjusted position.

This application is a substitute for and in part a continuation of my prior applications for patent on awning, Serial No. 411,100, 25 filed September 18, 1920, and Serial No. 429,955 filed December 11, 1920.

An illustrative embodiment of the invention is shown in the accompanying drawings, in which:—

30 Fig. 1 is a front elevation of a window with the improved awning applied thereto, the position of the awning being that which it assumes at the moment of being released;

Fig. 2 is a vertical section on line 2—2 of Fig. 1;

35 Figs. 3 and 4 are detail perspective views showing two different forms of one of the fittings;

Figs. 5 and 6 are each similar to Fig. 2, 40 but show different positions to which the awning may be adjusted, part of the canvas being omitted in Fig. 5 to avoid concealing some of the other parts;

Fig. 7 is a detail perspective view illustrating the manner in which the awning frame is firmly locked against accidental displacement by the wind or otherwise when the awning is completely lowered;

Fig. 8 is a detail perspective view of a 45 removable hinge for the awning frame, and

Fig. 9 is a detail perspective view of a detail of the canvas and rigging.

The canvas 10 of the awning is supported by and furls upon a spring roller 11, the 50 same being of usual construction and prefer-

ably equipped with the customary manually controlled pawl (not shown) designed to permit the roller to run free at all times when in use, but to prevent unwinding of the spring when the roller is removed from the window. As shown, the roller 11 is mounted at its opposite ends in fittings 12 and 13, one of which is slotted as usual to permit the roller to be put up and taken down exactly as is done with window shades.

To extend the awning, when lowered, the cross bar 14 of a bail-shaped frame is passed through a hem at the end of the canvas 10 and the arms 15 of said frame are pivotally supported to permit the frame to swing outwardly away from the window. As shown in Figs. 1, 2, 5, 6, 7 and 8, the inner ends of the arms 15 are pivotally mounted in fittings 16 applied to the blind stops of the window frame at about the level of the parting rail between the upper and lower sash. To permit complete removal of the awning from the window without detaching the fittings 16, each of these fittings, Fig. 8, 50 may be formed to provide a socket 29 to receive the headed and overturned end 26 of the corresponding arm 15. Under these circumstances each fitting 16 also preferably includes a pivoted latch 27, which swings over the end of the arm to prevent accidental 55 displacement of the same from the fitting. In using the form of construction illustrated in Fig. 4 the arms 15 of the awning frame will preferably each be formed with an eye (not shown) at its inner end, the fitting shown in Fig. 4 being provided with an integral apertured lug 34 through which a pivot pin (not shown) for entering said eye may be introduced.

In carrying out the invention the arms 15 of the awning frame are bent intermediate their ends to provide elbows, as 17, which engage the window frame below the fittings 16 while the cross bar 19 is located at a substantial distance outwardly 100 in front of the window. For cooperation with the frame in adjusting the awning to different positions and for locking the frame in its lowermost position, a stiffening rib or batten 19 is extended across the canvas 10 at a distance from its lower end preferably substantially equal to the length of the arms 15 beyond the elbows 17.

In order that the batten 19 will not interfere with the winding of the canvas upon the

2

spring roller 11, it preferably takes the form of a narrow metal strip which is curved in cross section to conform to the curvature of the roller, and is enclosed within a pocket 5 formed by applying a strip 21 of fabric to the canvas, over the batten (Fig. 9). In some positions of the awning the batten 19 serves for deflecting the canvas to such an extent that the unfurled part of the canvas 10 above the batten extends in a substantially vertical plane in front of the upper part of the window while the part of the canvas between the batten and the cross bar 14 of the awning frame is inclined and provides a 15 hood over the lower part of the window. For this purpose the pull cord, as 20, which serves for drawing the canvas from the spring roller 11 leads to the batten 19 rather than to the end of the canvas. As bending 20 of the batten is to be avoided, the cord 20 is attached thereto through a bridle 22 which connects with the batten at two widely separated points. The curved form of the batten also materially resists bending. 25

When the canvas is completely wound up on the spring roller 11, the bridle 22 and a part of the cord 20 are also wound upon the roller between the adjacent turns of the canvas. Pulling the cord accordingly serves to lower 30 the awning although the cord is not attached to the extreme end of the canvas. In this connection it will be observed that the bent form of the arms 15 of the awning frame insure that there will be a sufficient overhang of the frame in front of its pivotal connection with the fittings 16 to cause the frame to fall by gravity from its upright position whenever the canvas is drawn from the roller 11 by the cord. 35

The position of the awning illustrated in Fig. 6 is obtained by pulling upon the cord 20 until the canvas 10 has been lowered to the extent desired where it is held against the winding effort of the roller 11 by the 40 cord. For this purpose the cord will preferably be fastened at the bottom of the window, as upon a cleat 23 which may be applied to the window sill, outside of the sash. If desired a pulley 29, about which the cord turns, may be provided upon the same mounting with the cleat 23. In this position of the awning, weight of the awning frame is relied upon entirely for tensioning the extended part of the canvas. 45

Upon further lowering the canvas the elbows 17 of the arms 15 engage the window frame, as in Figs. 5 and 7. Since, when the awning is used at all in stormy weather, it will customarily be employed in this position, it is desirable that provision be made 50 for firmly holding it against being raised by the wind or the like. As shown, the batten 19 is made of such length that its ends 28 project beyond the canvas 10 at each side to 55 overlie the arms 15 of the awning frame and

downwardly and outwardly facing hooks 30, secured to the window frame below the fittings 16 at a distance slightly less than the length of the arms 15 above the elbows 17, are provided for receiving the projecting ends of the batten and urging the batten inwardly upon the said arms of the awning frame when the elbows 17 are engaged with the frame of the window. In this manner 70 the awning frame is securely locked in position and the canvas 10 is held taut and prevented from flopping in the wind. 75

In the form of construction illustrated in Figs. 1, 2, 3, 5, 6, and 7, the hooks 30 are formed upon fittings 31 which are applied to 80 the blind stops of the window below the fittings 16. To prevent the engagement of the projecting ends of the batten 19 with the hooks 30 when the awning is to be raised, the fittings 31 preferably each includes a 85 hinged gate piece 32 designed to close the hook opening when it is lifted by the batten, as in Fig. 2. To prevent the batten sliding over the end of the gate piece 32 before the gate piece has been lifted to a sufficient 90 height to close the hook opening, the lower edge of the gate piece is preferably notched, as at 33. In order to release the awning from the locked position it is only necessary to pull upon the cord 20, causing the 95 batten 19 to slide over and beyond the inclined upper edges of the gate pieces 32. On now slackening the cord the spring roller 11 will cause the batten 19 to engage the notches 33, thus swinging the gate pieces 100 upwardly for guiding the batten 19 clear of the hooks 30.

In the form of construction illustrated in Fig. 4, the hook 30 is formed upon a fitting 35 which also includes the bracket lug 34 to 105 which the corresponding arm 15 of the awning frame is pivotally attached. The fitting 35 includes a stationary part 36 for guarding the open end of the hook 30. When this form of construction is used the projecting ends of the batten become engaged with the hooks 30 only when the awning has been lowered to a position in which the batten just clears the ends of the hooks. If the awning is further lowered and then released, the guards 36 will so deflect the batten 110 during its upward movement as to prevent its engagement with the hooks. It follows that to release the awning from its locked position, it is only necessary to pull upon the cord 20 until the batten is lowered beyond the guards 36 and then release the cord in the same manner as when the form 115 of fitting illustrated in Fig. 3 is used. With either form of fitting, the ends of the batten when engaged with the hooks 30 are urged 120 inwardly upon the arms 15 of the awning frame due to the spring tension of the roller 11 and the downward and forward inclination of the hooks. There is accordingly no 130

opportunity for any movement of the awning frame under the influence of the wind or from any cause when it occupies its said locked position.

- 5 The awning is suitable for use at any time of the day. At noon, when the sun is hot and its rays directed almost vertically downward the canvas is only partly lowered and is held out from the window by the 10 arms 15, as in Fig. 6, thus allowing free circulation of air beneath the awning. Later in the day, when the rays are more nearly horizontal, but when the heat is not so intense, the awning is lowered to the position shown in Fig. 5, where the upper part of the canvas is closely drawn against the window, while the lower part only is sloping.

I claim as my invention:

- 20 1. In an awning, in combination, a horizontally disposed roller, a vertically swinging bail-shaped frame located below the roller and having its arms permanently bent in vertical planes intermediate their ends 25 to form elbows for contact with a supporting structure, and an awning canvas wound upon the roller and having its free end attached to the cross bar of the said bail-shaped frame.
- 30 2. In an awning, in combination, a horizontally disposed roller, a vertically swinging bail-shaped frame located below the roller and having its arms bent in vertical planes intermediate their ends to form elbows for 35 contact with a supporting structure, an awning canvas wound upon the roller and having its free end attached to the cross bar of the said bail-shaped frame, and means for deflecting the awning canvas at a distance 40 from its said free end when extended.
3. In an awning, in combination, a horizontally disposed spring roller, a vertically swinging bail-shaped frame located below the roller and having its arms bent in vertical planes intermediate their ends, an awning 45 canvas wound upon the roller and having its free end attached to the cross bar of the said bail-shaped frame, and means for drawing the canvas from the roller and deflecting the same when extended, said means being attached to the canvas at a distance from its said free end and adapted to wind upon the roller with the canvas.
4. In an awning, in combination, a horizontally disposed spring roller, a vertically swinging bail-shaped frame located below the roller and having its arms bent in vertical planes intermediate their ends, an awning 55 canvas wound upon the roller and having its free end attached to the cross bar of the said bail-shaped frame, a transverse stiffening rib applied to the canvas at a distance from its said free end and means engaging the said stiffening rib for deflecting the canvas when extended.

5. In combination, an awning canvas, a horizontally supported spring roller upon which the canvas is wound, a bail-shaped frame having its ends pivotally supported to swing upon a horizontal axis below the roller, the free end of the canvas being attached to the cross member of the said bail-shaped frame, a rigid batten extending across the canvas at a distance from its said free end, the ends of the batten projecting beyond the canvas and a pair of downwardly facing stationary hooks for receiving the said projecting ends of the batten.

6. In combination, an awning canvas, a horizontally supported spring roller upon which said canvas is wound, a bail-shaped frame having its arms pivotally supported to swing upon a horizontal axis below the roller, the free end of the canvas being attached to the cross member of the said bail-shaped frame, a rigid batten extending across the canvas at a distance from its said free end, the ends of the batten projecting beyond the canvas, and over the arms of said bail-shaped frame, and a pair of downwardly facing, stationary hooks for receiving the said projecting ends of the batten.

7. In combination, an awning canvas, a horizontally supported spring roller upon which said canvas is wound, a bail-shaped frame having its arms bent in vertical planes intermediate their ends and pivotally supported to swing said frame upon a horizontal axis below the roller, the free end of the canvas being attached to the cross member of the said bail-shaped frame, a rigid batten extending across the canvas at a distance from its said free end, the ends of the batten projecting beyond the canvas and over the arms of said bail-shaped frame, and a pair of downwardly facing, stationary hooks for receiving the said projecting ends of the batten.

8. In an awning, in combination, a spring roller secured in a window frame, an awning canvas carried by said roller, a swinging bail-shaped frame, having its arms bent in vertical planes intermediate their ends, to the cross bar of which the lower end of the awning canvas is attached, a transverse stiffening rib applied to the awning at a distance from said lower end, the ends of said rib projecting beyond the canvas, fixtures secured to said window frame, comprising hooks for engaging said projecting ends and an arm hinged below each of said hooks for lifting said rib clear of said hooks.

9. In an awning, in combination, a spring roller secured in a window frame, an awning canvas carried by said roller, a swinging bail-shaped frame having its arms bent in vertical planes intermediate their ends, to

the cross bar of which the lower end of the awning canvas is attached, a transverse stiffening rib applied to the awning at a distance from said lower end, the ends of said rib projecting beyond the canvas and hooks secured to said window frame for engaging said projecting ends and holding said vertically bent arms in position beneath said rib.

10. The combination with a window frame, of a stiff bail-shaped awning frame having its two ends pivotally mounted upon the side members of the window frame to permit swinging of the said awning frame outwardly in front of the window frame upon a horizontal axis, the two side members of the awning frame being bent in vertical planes to provide downwardly facing elbows intermediate their ends for engagement with the window frame to limit the downward movement of the awning frame when the outer end portions of the said two side members beyond the elbows are in an approximately horizontal position.

11. The combination with a window frame, of an awning roller extending horizontally across the top of the window frame, a stiff bail-shaped awning frame having its two ends pivotally mounted upon the side members of the window frame to permit swinging of the said awning frame outwardly in front of the window frame upon a horizontal axis, and an awning canvas mounted upon the awning roller and having its free end attached to the intermediate transverse portion of the said bail-shaped awning frame, the two side members of the awning frame being bent in vertical planes to provide downwardly facing elbows intermediate their ends for engagement with the window frame to limit the downward movement of the awning frame when the outer end portion of the said two side members beyond the elbows are in an approximately horizontal position.

12. The combination with a window frame, of an awning roller extending horizontally across the top of the window frame, a stiff bail-shaped awning frame having its two ends pivotally mounted upon the side members of the window frame to permit swinging of the said awning frame outwardly in front of the window frame upon a horizontal axis, an awning canvas mounted upon the awning roller and having its free end attached to the intermediate transverse portion of the said bail-shaped awning frame, the two side members of the awning frame being bent in vertical planes to provide downwardly facing elbows intermediate their ends for engagement with the window frame to limit the downward movement of the awning frame when the outer end portions of the said two side members beyond the elbows are in an approximately hori-

zontal position, a stiff batten transversely mounted upon the awning canvas at a distance from its said free end approximately equal to the length of the said outer end portions of the two side members of the awning frame beyond the elbows, and a pull cord attached to the batten.

13. The combination with a window frame, of an awning roller extending horizontally across the top of the window frame, a stiff bail-shaped awning frame having its two ends pivotally mounted upon the side members of the window frame to permit swinging of the said awning frame outwardly in front of the window frame upon a horizontal axis, an awning canvas mounted upon the awning roller and having its free end attached to the intermediate transverse portion of the said bail-shaped awning frame, the two side members of the awning frame being bent in vertical planes to provide downwardly facing elbows intermediate their ends for engagement with the window frame to limit the downward movement of the awning frame when the outer end portions of the said two side members beyond the elbows are in an approximately horizontal position, a stiff batten transversely mounted upon the awning canvas at a distance from its said free end approximately equal to the length of the said outer end portions of the two side members of the awning frame beyond the elbows, the length of the batten being greater than the width of the awning frame whereby the ends of the batten overlie the side members of the awning frame when the canvas is lowered, and a pull cord attached to the batten.

14. The combination with a window frame, of an awning roller extending horizontally across the top of the window frame, a stiff bail-shaped awning frame having its two ends pivotally mounted upon the side members of the window frame to permit swinging of the said awning frame outwardly in front of the window frame upon a horizontal axis, an awning canvas mounted upon the awning roller and having its free end attached to the intermediate transverse portion of the said bail-shaped awning frame, the two side members of the awning frame being bent in vertical planes to provide downwardly facing elbows intermediate their ends for engagement with the window frame to limit the downward movement of the awning frame when the outer end portions of the said two side members beyond the elbows are in an approximately horizontal position, a stiff batten transversely mounted upon the awning canvas at a distance from its said free end approximately equal to the length of the said outer end portions of the two side members of the awning frame beyond the elbows, the length of the batten being greater than the width

of the awning frame whereby the ends of the batten overlie the side members of the awning frame when the canvas is lowered, and a pair of catches mounted upon the side members of the window frame adjacent the points of engagement therewith of the said elbows for receiving the ends of the batten.

15. In an awning, the combination of a horizontally disposed roller, a vertical swinging bail-shaped frame located below the roller, an awning canvas wound upon the roller and having its free end attached to the cross bar of the bail-shaped frame, and means for deflecting the awning canvas at a distance from its said free end and securing said bail-shaped frame against swinging.

16. In an awning, the combination of a horizontally disposed spring roller, a vertical swinging bail-shaped frame located below the roller and having its arms bent in vertical planes intermediate their ends, an awning canvas wound upon the roller and having its free end attached to the cross bar of said bail-shaped frame, a transverse stiffening rib applied to the canvas at a distance from said free end and means for engaging said stiffening rib to deflect the canvas and hold the bail-shaped frame against swinging.

17. In combination, an awning canvas, a horizontally supported spring roller upon which the canvas is wound, a bail-shaped frame having its ends pivotally supported to swing upon a horizontal axis below the roller, the free end of the canvas being attached to the cross member of the said bail-shaped frame, a rigid batten extending across the canvas at a distance from its said free end, the ends of the batten projecting beyond the canvas, a pair of downwardly facing stationary hooks for receiving the said projecting ends of the batten, and guards to prevent engagement of the batten with the hooks in raising the awning.

18. In combination, an awning canvas, a horizontally supported spring roller upon which the canvas is wound, a bail-shaped

frame having its ends pivotally supported to swing upon a horizontal axis below the roller, the free end of the canvas being attached to the cross member of the said bail-shaped frame, a rigid batten extending across the canvas at a distance from its said free end, the ends of the batten projecting beyond the canvas, a pair of downwardly facing stationary hooks for receiving the said projecting ends of the batten, and gates pivoted below said hooks for engaging said batten when the awning is raised.

19. In an awning, the combination of a supporting frame, a horizontally disposed roller mounted on said frame, a vertical swinging bail-shaped frame pivoted below said roller and having means to support the outer portion thereof at an angle to the supporting frame, an awning canvas wound upon the roller and having its free end attached to the cross bar of the bail-shaped frame, and means for deflecting the canvas and securing it to the supporting frame below the pivot of the bail-shaped frame.

20. In an awning, the combination of a supporting frame, a horizontally disposed roller mounted on said frame, a vertical swinging bail shaped frame pivoted below said roller and having means to support the outer portion thereof at an angle to the supporting frame, an awning canvas wound upon the roller and having its free end attached to the cross bar of the bail-shaped frame, and a common means for deflecting the canvas and securing the bail-shaped frame in extended position.

21. In an awning, the combination with the supporting frame, a roller rotatably mounted on the frame, a bail-shaped frame pivoted on the supporting frame below said roller and having its arms bent at points removed from the pivotal axis to form elbows for holding the outer portion of the bail-shaped frame away from the supporting frame and an awning canvas wound on said roller with one end attached to the bail-shaped frame.

DAVID H. HARNLY.
